UNITED STATES PATENT OFFICE

2,420,184

COVER FASTENING DEVICE

Harold L. Mekelburg, Milwaukee, Wis., assignor
to Cutler-Hammer, Inc., Milwaukee, Wis., a corporation of Delaware

Application November 3, 1944, Serial No. 561,787

3 Claims. (Cl. 220—55)

1

This invention relates to enclosing casings for electrical control apparatus such as drum controllers and more particularly to cover fastening devices therefor.

Drum controllers are usually provided with an enclosing casing consisting of a rear casing section and a removable U-shaped front cover member which fits over the back and end walls on the rear casing section to provide a complete enclosure for the contact mechanism of the controller. Heretofore the cover member was usually secured to the rear casing section by means of eye bolts located on the exterior of the enclosing casing. However, this type of securing means has been found objectionable for various reasons, as for example, the same increases the overall dimensions of the controller and is not satisfactory from the standpoint of modern streamline design.

The present invention has among its objects to provide an improved cover securing mechanism for controllers of the aforesaid type which overcomes the aforementioned objections.

Another object is to provide a concealed cover securing means for controllers of the aforesaid type which is exceedingly simple, rugged, and inexpensive in construction and which provides a spring holding force for maintaining the cover member in tight engagement with the back and end walls of the rear casing section.

Various other objects and advantages of the invention will hereinafter appear.

The accompanying drawing illustrates an embodiment of the invention which will now be described, it being understood that the embodiment illustrated is susceptible of modification without departing from the spirit and scope of the appended claims.

In the drawing,

Figure 1 is a perspective view of a drum controller casing embodying the invention, the front cover of the casing being shown detached from the rear section thereof.

Fig. 2 is a transverse sectional view of the enclosing casing shown in Fig. 1 illustrating one side of the cover in attached position and the other in a loosened position, and

Fig. 3 is a fragmentary sectional view on line 3—3 of Fig. 2.

Referring to Fig. 1, the same illustrates an enclosing casing of the type commonly employed in drum controllers, including a rear casing section 1 and a front cover 2. The rear casing section 1 is provided with a rectangular back plate 3 having forwardly extending rectangular

2

end walls 4—4 formed on opposite ends thereof. Cover 2 comprises a U-shaped sheet metal member which is formed to fit over the end walls 4 and to straddle the back plate 3. The front and side walls of cover 2 are provided with inwardly bent end portions 5 (Fig. 3) and as shown in Fig. 1, the side walls of said cover are normally disposed in diverging relation to require springing thereof toward each other for engagement with the side edges of end walls 4 and back plate 3.

In the embodiment illustrated, the front and side walls of cover 2 are provided with end strip gaskets 6 (Fig. 3) for engaging the front and side edges of end walls 4 and the side walls 15 are also provided with strip gaskets 7 (Fig. 2) for engaging the side edges of back plate 3. These gaskets are cemented to the inner face of cover 2 and are usually formed of felt for dust-proofing of the casing or of rubber for water-proofing 20 thereof. However, the gaskets may be omitted where it is unnecessary to protect against dust or water. As shown in Fig. 3 the inwardly bent portions 5 on opposite ends of cover 2 serve as abutments for the end strip gaskets 6 and each 25 of the side strip gaskets 7 has a sheet metal retaining strip 8 associated therewith, which is secured to the cover by spot welding.

As will now be set forth, the side walls of cover 2 are provided with fastening devices 9 which 30 act in applied fastening position to exert a spring holding force on said cover for maintaining the same in tight engagement with the side edges of back plate 3 and also with the front and side edges of end walls 4. In the embodiment illustrated each of the side walls of cover 2 is provided with a single fastening device 9 which is located midway between the ends thereof, but, as is apparent, each side wall may be provided with a plurality of fastening devices if 35 desired.

Each of the fastening devices 9 consists of a screw 10 and an associated screw-receiving bracket 11 formed from a resilient sheet metal strip which is bent to provide arms 12 and 13 45 which are disposed in oblique angular relation, the former arm constituting a base portion and the latter having a tapped screw-receiving portion 14 on the free end thereof. The base portions 12 of brackets 11 are secured to the front face of back plate 3 either by welding or by means of rivets and as shown in Fig. 2 the arms 13 of said brackets extend forwardly from said back plate and toward opposite sides thereof. Also as shown on the right-hand side of Fig. 2, 55 the brackets 11 are located with respect to the

side edges of back plate 3 so that the screw-receiving portions 14 thereof are normally spaced inwardly a short distance with respect to said edges. The screws 10 are insertable through openings 15 in the side walls of cover 2 for engagement within the tapped openings in the portions 14 of brackets 11 and the outer ends of said screws are provided with slotted heads 16 for engaging said walls on the outer side thereof.

When cover 2 is placed upon the rear casing section 1 with the front wall thereof in engagement with the front edges of end walls 4, screws 10 will register with the tapped openings in the portions 14 of brackets 11 when the same are inserted through the openings 15 in the side walls of said covers. As hereinbefore stated the side walls of cover 2 are normally disposed in diverging relation to require springing thereof toward each other for engagement with the side edges of back plate 3 and end walls 4. When screws 10 are screwed into the portions 14 of brackets 11 the side walls of cover 2 are drawn toward each other for engagement with the side edges of back plate 3 and end walls 4 and upon tightening of said screws the arms 13 of said brackets are deflected out of the normal position illustrated on the right-hand side of Fig. 2 into the position illustrated on the left-hand side of this figure. This deflection of the brackets 11 subjects the screws 10 to a spring force which tends to move the same axially and also laterally toward the back plate 3 whereby cover 2 is held in firm engagement not only with the side edges of back plate 3 and end walls 4 but also with the front edges of said end walls.

What I claim as new and desire to secure by Letters Patent is:

1. The combination with a rear casing section having a rear wall and forwardly extending end walls, a U-shaped cover formed to fit over said end walls and to straddle the side edges of said rear wall and securing means for said cover comprising resilient brackets secured to said rear wall and having screw-receiving arms extending forwardly and toward opposite sides of said rear wall, and securing screws associated with said brackets and extending through openings in the side walls of said cover, the screw-receiving arms of said brackets being deflected when said screws are in applied fastening position to exert a spring-holding force on said cover for holding the side walls thereof in firm engagement with the side edges of said rear wall and said end walls, for also holding the front wall of said cover in firm engagement with the front edges of said end walls.

2. The combination with a rear casing section having a rear wall and forwardly extending end

walls, a U-shaped front cover to fit over the front and side edges of the end walls of said rear casing section and to straddle the rear wall thereof, and securing means for said cover comprising screws extending through openings in the side walls of said cover and brackets secured to the rear wall of said casing, each having a forwardly extending resilient arm provided with a tapped opening for receiving one of said screws, said resilient arms being normally spaced inwardly with respect to the side edges of said rear wall and being deflected outwardly with respect thereto upon tightening of their associated screws to draw the side walls of said cover inwardly and rearwardly with respect to said rear casing section for tight engagement of said cover with the front and side edges of said rear casing section.

3. The combination with a rear casing section having a rear wall and forwardly extending end walls, a U-shaped cover formed to fit over the front and side edges of the end walls of said rear casing section and to straddle the rear wall thereof, the side walls of said cover being normally disposed in diverging relation to require springing thereof toward each other for engagement with the side edges of said rear casing section, and securing means for said cover comprising screws extending through openings in the side walls of said cover and brackets secured to the rear wall of said casing section each having a forwardly extending resilient arm provided with a tapped opening for receiving one of said screws, said resilient arms being normally spaced inwardly with respect to the side edges of said rear wall and being deflected outwardly with respect thereto upon tightening of said screws to draw the side walls of said cover rearwardly and inwardly with respect to said rear casing section for tight engagement of said cover with the front and side edges of said rear casing section.
